UNITED STATES PATENT OFFICE.

RICHARD J. ZANONE, OF NEW ALBANY, INDIANA, ASSIGNOR TO THE AUTOMATIC PACKAGE SCALE COMPANY, OF LOUISVILLE, KENTUCKY, A CORPORATION OF KENTUCKY.

AUTOMATIC SCALE.

1,243,791.

Specification of Letters Patent.

Patented Oct. 23, 1917.

Application filed December 20, 1915. Serial No. 67,788.

To all whom it may concern:

Be it known that I, RICHARD J. ZANONE, a citizen of the United States, residing in the city of New Albany, county of Floyd, and 5 State of Indiana, have invented certain new and useful Improvements in Automatic Scales, of which the following is a specification.

This invention relates to automatic scales 10 adapted to weigh commodities of various classes, such as corn meal, chicken feed, etc., either continuously or intermittently.

An object of this invention is to provide a device of the character described, which 15 shall be economical in construction, accurate in operation, and durable in service.

With the foregoing and other objects in view, the invention consists of the novel construction and arrangement of parts illustrated in the accompanying drawing, which 20 forms a part of this specification, wherein is set forth an embodiment of the invention, but it is to be understood that such changes and modifications may be resorted 25 to as come within the scope of the appended claims.

Referring to the drawing wherein similar 30 reference characters designate like parts in the several views Figure 1, is a perspective view of an embodiment of the invention showing the various parts in normal position, *i. e.* ready to receive a commodity to be weighed, portions being broken away to show the construction; Fig. 2, a side view of 35 the upper portion, partly in elevation and partly in section, showing the weighing hopper borne down by a contained weighed portion, the mechanism not being set to automatically release the bottom of the hopper to discharge its contents; Fig. 3, a view 40 similar to Fig. 2, showing the parts in the position assumed in discharging a weighed portion, the mechanism being set to automatically release the bottom of the hopper; Fig. 4, a view similar to Fig. 3, showing the 45 position of the parts when the weighing hopper rises after being lightened of a portion of its contents, the feed gate remaining closed as long as the bottom of the 50 hopper is held open; Fig. 5, a plan view with the top removed; Fig. 6, a perspective of the gate locking lever; Fig. 7, a perspective view of the tripping lever; Fig. 8, a perspective view of the feed gate operating 55 lever.

Referring in detail to the drawing the reference numeral —1— designates a frame, preferably constructed of angle iron, suitably braced, and carrying a top —2—. A receiving hopper —3— is supported by the top, the downward converging walls of which lead to a chute —4—. The delivery chute 4 depends through an opening —5— in the top. A gate —6— is pivotally attached to the sides of the chute, the point of suspension being forward of the center of gravity so that the gate tends to close by gravity. The gate closes against the bristles of a brush —7— which is secured to the front of the chute. A scale beam comprising a pair of parallel arms —8, 9— held in spaced relationship by means of transverse bars —10— —11— is pivotally supported, in brackets —12— which depend from the top, by means of pivots —13—. 70 A poise weight —14— is adapted to be adjusted along one of the arms. A counter balance weight —15— is suitably suspended from the rear of the scale beam. A gate operating lever —16— is pivotally mounted 75 between two brackets —17, 18—, which depend from the top. This lever comprises a relatively long vertical arm —19— and a short horizontal arm —20—. The vertical arm is connected by means of a rod —21— with the gate, the arrangement being such that when the arm 19 is in a normal, or vertical position, the gate is open, and when it is released the gate closes. The arm 19 is held in its normal position by means of a 80 latch —22— carried on a trip lever —23—, which engages with the upper end of the arm. The latch is pivoted on the trip lever, preferably co-incidently therewith, the rear end resting on a pin —24—, extended from 85 the side of the lever, the arrangement being such that the latch will rise, to permit the arm 19 to return to its normal position, without raising the lever, but when the lever is raised it carries the latch with it 90 releasing the arm and permitting the gate to close. On the inner side of the transverse bar 10, of the scale beam, is a horizontal projection —25— which comes into contact with the arm 20 of the gate lever and returns it to and maintains it in, its normal position, thus holding the gate open as long as the rear end of the scale beam is depressed. A vertical projection —26— from 95 the bar 10, engages with and raises the rear 100 105 110

end of the trip lever as the rear end of the scale beam approaches the upper limit of its travel. A weighing hopper —27— is suspended from the forward ends of the scale beam by suitable means such as ears —28—. The weighing hopper comprises vertical sides and a drop bottom, or closure —29— suitably hinged as at —30—. A counter weight —31— serves to return the bottom when open, to a closed position, in which it is retained, when charged, by catches —32—, pivoted on the sides of the hopper, which engage with detents —32— on the drop bottom. The horizontal arms of the catches 32 extend forward beyond the hopper in position to be engaged with, or by a trip lever —33—, to release the bottom 29. A delivery funnel —34— supported beneath the weighing hopper in position to receive commodity discharged therefrom, is carried by bars —35—, and projects slightly forward from the frame. The lever 33 is pivotally mounted within the funnel 34, in position to actuate the catches 32, comprises a transverse contact bar —37—, arms —38— which lead from the ends of the contact bars to pivotal points —39—, a vertical stem —40—, with a lateral forward extension which projects over the upper edge of the funnel into position to be impinged upon by a rod —41— which is mounted in brackets —42, 43— on the front of the funnel. When the trip lever 33 is in its lowest position the catches will not contact with the bar 37 to release the bottom of the weighing hopper. This lever may be retained in its elevated position by engaging a stop —44— on the rod 41 with the bracket 42; when the lever is in the elevated position the catches will engage with the contact bar 37 at every descent of the hopper and the weighing operation will proceed continuously or as long as the commodity is furnished to the weighing hopper (see Fig. 3).

In operation the poise being set at the amount it is desired to weigh a commodity is conducted, either intermittently or continuously, from a suitable source of supply, into the receiving hopper, hence it flows into the weighing hopper. When the weighing hopper has received a quantity sufficient to counter-balance the weight on the scale beam, it will descend. As the rear end of the scale beam rises, under influence of the weighted hopper, the projection 25 leaves the arm 20 of the gate 16. This would permit the gate 6 to close, but that the lever 16 is restrained by the latch 22. It is to be observed that at the moment that the scale beam is in equilibrium the weighing hopper hangs free from connection or contact with any actuating or controlling means which would tend to retard its movement, or interfere with the accuracy of the weighing operation. As the scale beam rises above the horizontal the vertical projection 26 contacts with, and raises, the trip lever 23, and with it the latch 22. This releases the gate lever and permits the feed gate to close, shutting off the flow of commodity into the weighing hopper. As the feed gate closes, the forward end of an arm —45—, the rear end of which is suitably pivoted on the brackets 17, 18 engages with a projection, or notch, —46— on the rod 21, and locks the gate in its closed position. The scale beam has a slight travel, after contacting with the trip lever, before it is brought to a standstill by the contact of the trip lever 23, with the frame (see Fig. 2). In this position the charged weighing hopper, remains suspended until the catches 32 are released from engagement with the bottom, when the weight of the contained commodity causes the bottom to open, the outflowing commodity holding it open. As soon as lightened by escape of a portion of the contained commodity, the weight on the scale beam returns the weighing hopper to its normal elevated position (see Fig. 4). As the rear end of the scale beam descends, the projection 25 contacts with the arm 20, of the gate lever, and would open the feed gate but that it is held by the lever 45, which is in engagement with the rod 21 at 46. As the gate lever returns to its normal position the latch 22 rises and permits the arm 19 to pass without moving the trip lever 27. When the flow of commodity, from the weighing hopper ceases, the counter-balance weight 31 will cause the bottom to close. A shaft —47— mounted in brackets —48—, on the rear wall of the weighing hopper near the top thereof has radial extensions —49— and —50—, one of which 49, is connected by means of a rod —51— with the arm which carries the weight 31; the arrangement being such that as the bottom closes the shaft 47 will be partially rotated bringing the projection 50 into contact with the lower end of a leg —52—, which depends from the lever 45, raising said lever from its engagement with the projection 46 on the rod 21, and permitting the feed gate to be opened by the pressure of the rear end of the scale beam on the gate lever 16. It will be seen that with the lever 33 raised, the weighing will proceed continuously and automatically and that with said lever lowered single packages may be weighed.

Having thus described my invention so that anyone skilled in the art pertaining thereto may make and use the same, I claim:

1. In a scale, a frame, a scale beam pivoted thereon, a hopper suspended from said beam, a hinged drop bottom on said hopper, catches pivotally attached to the sides of the hopper and adapted to engage and retain the bottom in a closed position, a funnel

nel in fixed relationship to the frame positioned below the hopper and means within the funnel adapted to be moved into engagement with said catch to release the 5 bottom.

2. In a scale, a frame, a scale beam pivoted thereon, a hopper suspended from said beam, a hinged drop bottom on said hopper, catches pivotally attached to the sides of 10 the hopper and adapted to engage and retain the bottom in a closed position, a funnel in fixed relationship to the frame positioned below the hopper and means within the funnel to be moved into position for 15 said catch to contact therewith as the hopper descends and release the bottom.

3. In a scale, a frame, a receiving hopper having a bottom outlet, a gate adapted to close said outlet, a bell crank lever, a rod 20 operatively connecting said gate and lever whereby they move in unison, a scale beam, the rear end of said beam adapted to contact with, and depress said lever to open the gate, a weighing hopper suspended 25 from the beam, a closure for said hopper, and means for preventing the opening of the gate while said closure is open.

4. In a scale, a frame, a receiving hopper having a bottom outlet, a gate adapted to 30 close said outlet, a bell crank lever, a rod operatively connecting said lever and gate whereby they move in unison, a scale beam, the rear end of said beam adapted to contact with, and depress said lever to open the 35 gate, a weighing hopper suspended from the beam, a closure for said hopper, holding means adapted to prevent the opening of the gate and means operable by the closing of said closure to release said holding 40 means.

5. In a scale, a scale beam, a weighing hopper suspended from the forward end thereof, a chute for delivering material to said hopper, a gate for said chute, a closure for the hopper, means operable by the rear end of said beam on the downward movement thereof to open said gate, and means for rendering said opening ineffective while said closure is open.

50 6. In a scale, a scale beam, a weighing

hopper suspended from the forward end thereof, a chute for delivering material to said hopper, a gate for said chute, a closure for the hopper, means operable by the rear end of said beam on the downward movement thereof to open said gate, means for locking said gate in a closed position, and means controlled by the closing of said closure to release said locking means. 55

7. In a scale, a scale beam, a hopper suspended from the forward end thereof, a chute for delivering material to said hopper, a gate for said chute, a lever engageable by the rear end of said scale beam on the downward movement thereof, a rod connecting said lever and gate, a detent adapted to engage with said rod when the gate is closed, a closure for said hopper, and means operable by the closing of said closure to release said detent. 70

8. In a scale, a scale beam, a hopper suspended from the forward end thereof, a chute for delivering material to said hopper, a gate for said chute, a lever engageable by the rear end of said scale beam on the downward movement thereof, a rod connecting said lever and the gate, a detent adapted to engage said rod when the gate is closed, a closure for said hopper, a rock shaft mounted on the hopper, operative connections between said closure and said shaft, and an arm extended from the shaft and adapted to be moved into position to engage and release said detent upon the closing of said closure. 75

9. In a scale, a scale beam, a hopper suspended from the forward end thereof, a chute for delivering material to said hopper, a gate for said chute, a lever engageable by the rear end of said scale beam on the downward movement thereof, a rod connecting said lever and gate, a detent adapted to engage said rod when the gate is closed, a closure for said hopper, and a rock shaft mounted on the hopper, having arms extended therefrom, one of which is connected with the closure and the other adapted to be moved into position to engage with and release said detent. 90 95

RICHARD J. ZANONE.
